UNITED STATES PATENT OFFICE.

BERNHARD BENEDIX, OF HAMBURG, GERMANY.

FATTY SAPONACEOUS PRODUCT AND METHOD OF MANUFACTURING SAME.

1,102,129.

Specification of Letters Patent. Patented June 30, 1914.

No Drawing.

Application filed July 23, 1912. Serial No. 711,097.

To all whom it may concern:

Be it known that I, BERNHARD BENEDIX, citizen of the free town of Hamburg, residing at 21 Grosse - Theater strasse, city of Hamburg, German Empire, have invented certain new and useful Improved Fatty Saponaceous Product and Method of Manufacturing Same, of which the following is a specification.

10 This invention relates to an improved product of the nature of soap for use in laundries and the like and the method of manufacturing the same from hydrocarbons.

In the manufacture of soap from hydrocarbons it has already been proposed to oxidize the hydrocarbons by mixing them with alkalis and passing air or oxygen therethrough under the application of heat. The hydrocarbons which can be employed for this purpose decompose, however, at high temperatures, so that an attempt to obtain soaps as aforesaid, proved futile. Moreover, if, as has been suggested, the operation is carried out under pressure, the attempt to oxidize the hydrocarbons would be extremely dangerous.

According to the present invention, the hydrocarbons, for example vaseline oil, are intimately mixed in the presence of water with sodium or hydrogen peroxid admixed with alkalis or alkaline salts. In this manner, a stronger action of the oxygen upon the individual hydrocarbon molecules is attained so that the hydrocarbons become oxidized to acids by the oxygen generated during the process, the acids forming, with the alkalis added or resulting from the sodium peroxid and with the excess hydrocarbon, a mass easily soluble in water and applicable as a soap. Whereas, in the known methods, large quantities of the hydrocarbons are not oxidized, thus giving a poor yield, it is possible by the present process to oxidize up to 60% of the hydrocarbons. The intimate mixture and the reaction of the materials therein can also be accelerated, if desired, by the addition of alcohol.

The following example is given of the method of preparing my improved product from a quarter of a liter of vaseline oil. A mixture is first of all made of about 50 grams of crystal soda, 20 grams of potash and 5 grams of sodium peroxid. The mixture is effected by the addition of water, sufficient water being added as to form a

thick paste. Thereupon about 5 grams of alcohol may be added to the mixture which is then intimately mixed with the vaseline oil. After slightly stirring, the mixture thickens and more water may be added if required.

The finished product is a soft paste having good cleansing properties and easily soluble in water.

I claim:

1. The method of obtaining a cleansing product from vaseline oil, which consists in intimately mixing the vaseline oil with a mixture of a peroxid and an alkali in the presence of water.

2. The method of obtaining a cleansing product from vaseline oil, which consists in intimately mixing the vaseline oil with a mixture of a peroxid and an alkali in the presence of water and alcohol.

3. The method of obtaining a cleansing product from vaseline oil, which consists in intimately mixing the vaseline oil with a mixture of an alkaline peroxid and an alkali in the presence of water.

4. The method of obtaining a cleansing product from vaseline oil, which consists in intimately mixing the vaseline oil with a mixture of sodium peroxid and an alkali in the presence of water.

5. The method of obtaining a cleansing product from vaseline oil, which consists in intimately mixing the vaseline oil with a mixture of a peroxid and an alkaline salt in the presence of water.

6. The method of obtaining a cleansing product from vaseline oil, which consists in intimately mixing the vaseline oil with a mixture of a peroxid and an alkaline salt in the presence of water and alcohol.

7. The method of obtaining a cleansing product from vaseline oil, which consists in intimately mixing the vaseline oil with a mixture of sodium peroxid, soda and potash in the presence of water.

8. The method of obtaining a cleansing product from vaseline oil, which consists in intimately mixing the vaseline oil with a mixture of sodium peroxid, soda and potash in the presence of water and alcohol.

9. The method of obtaining a cleansing product from vaseline oil, which consists in intimately mixing the following substances in about the following proportions: a quarter of a liter of vaseline oil, 50 grams of soda, 110

65

70

75

80

85

90

95

100

105

20 grams of potash and 5 grams of sodium peroxid in the presence of water.

10. The method of obtaining a cleansing product from vaseline oil, which consists in intimately mixing the following substances in about the following proportions: a quarter of a liter of vaseline oil, 50 grams of soda, 20 grams of potash, 5 grams of so-

dium peroxid and 5 grams of alcohol in the presence of water.

In testimony whereof I have affixed my signature in presence of two witnesses.

BERNHARD BENEDIX.

Witnesses:

RUDOLF KRAUS,

ERNEST H. L. MUMMENHOFF.
